UNITED STATES PATENT OFFICE.

ARTHUR A. CRAIG, OF CHICAGO, ILLINOIS.

WINDOW VENTILATOR.

Application filed July 31, 1922. Serial No. 578,545.

My invention relates to window ventilators of the type adapted for insertion in a window frame, and held in place by frictional engagement between their ends and the sash members, and the invention may be considered as an improvement over the structure disclosed in my Patent No. 1,524,024, of January 27, 1925. In the arrangement of this patent, the sealing strips of ¹⁰ U-cross section are entirely backed by rigid and unyielding plates so that the window frame engaging edges of the sealing strips will not be sufficiently flexible to insure perfect engagement and seal where a window frame may be out of plumb or otherwise distorted. The object of my present invention is to acquire the necessary flexibility by providing the strips with air space behind their frame engaging edges so as to give the ventilator a wide range of accommodation to surfaces which are uneven and out of true alignment.

Referring to the drawings,

Figure 1 is a view of the parts for forming a sealing unit and illustrating the manner of assembling such parts;

Fig. 2 is an assembled view of the parts;

Fig. 3 is a similar view showing the parts secured together;

Fig. 4 is an isometric view of a ventilator with the sealing unit attached thereto and showing also an arrangement for securing the panel sections together;

Fig. 5 is an enlarged cross sectional view on plane 5-5 Figure 4; and

Fig. 6 is a plan view illustrating a slightly modified form of assembly of a ventilator section and sealing unit.

Referring to Fig. 1, 30 represents a rectangular piece of resilient material such as rubber and 31 represents the metal clips of U-shaped cross section which are slipped over the longitudinal ends of the material and then placed under pressure in order to tightly clamp the material. Fig. 2 shows the sealing material or member 30 bent on a line midway between the metal strips 31 to bring such metal strips against each other and into parallelism, and as the material 30

was made of sufficient width it will extend ⁵⁰ a sufficient distance beyond the outer edges of the strips to leave an air pocket or space A within the bend or fold of the material. Securing means such as tacks or rivets 33 may be applied along the strips to secure them ⁵⁵ together in alinement as shown in Fig. 3.

Referring to Fig. 4, the panel structure shown comprises the sections 4 and 5 which are held together in adjusted positions by means of metal U-shaped clips 35 secured by ⁶⁰ one arm to a panel as by means of rivets 36 and engaging with the other arm along the outside of the other panel, said other arms extending to the bottom edge of the panel for riding in a groove 37 formed by turning ⁶⁵ over the edge of the panel. After the proper adjustment of the ventilator panels has been made for the window frame to be fitted, the panels are clamped together by wing bolts 39 carried by the clips, as clearly ⁷⁰ shown in Fig. 5.

At the outer end of each panel are secured a pair of sealing units, the units being applied against the opposite faces of the panel with the outer edges of the strips 31 ⁷⁵ registering with the panel edge and with the free and air pocketed ends of the sealing material extending beyond the units and panel end, and the units may be secured to the panel as by means of rivets 33'.

Fig. 6 illustrates an alternative form of construction in which the sealing units are carried in a double U-socket 40 which receives the panel end to properly align the sealing ends of the units.

With the air pocketed projecting ends of the resilient sealing material irregularities in the sides of the window frames will be fully compensated for. Where the window frame sides are not perpendicular to the sill, ⁹⁰ the yielding air pocketed ends of the sealing units will never-the-less accommodate themselves to such irregularity and engage snugly and with sealing fit against the frame sides while the lower edges of the ⁹⁵ ventilator panels rest against the sill.

Having described my invention, I claim as follows:

In combination with an end of a panel type ventilator, a retaining element including a plurality of strips of yielding material bent longitudinally into the form of a **U** and having **U**-shaped strips of unyielding material fitted over the edges thereof to confine an air pocket therein and space the sides

of the **U** from each other, and means for securing the unyielding strips and the confined portions of the yielding strips to the 10 said end of said ventilator.

In witness whereof, I hereunto subscribe my name this 27th day of July, 1922.

ARTHUR A. CRAIG.
